UNITED STATES PATENT OFFICE

BERNARD H. ZIEHLER, OF DAYTON, OHIO.

PERMUTATION-LOCK.

1,078,120.

Specification of Letters Patent. Patented Nov. 11, 1913.

Application filed September 21, 1912. Serial No. 721,303.

To all whom it may concern:

Be it known that I, BERNARD H. ZIEHLER, a citizen of the United States, residing at Dayton, in the county of Montgomery and State of Ohio, have invented certain new and useful Improvements in Permutation- Locks, of which the following is a specification.

My invention relates to locks and particularly to combination or permutation locks.

The invention is applicable to doors, chests or other similar uses and is especially adapted for locking against movement any movable member such as the control lever of an automobile or other machine.

The object of the invention is to simplify the structure as well as the means and mode of operation of such devices whereby they will not only be cheapened in construction but will be more efficient in use, positive in action, readily adjusted and unlikely to get out of repair.

Further objects of the invention are to provide improved means for advancing the permutation disks or tumblers throughout a step by step movement and to facilitate the adjustment of the mechanism to operate upon different combinations.

A further object of the invention is to provide means for positively engaging the locking bolt in its adjusted or locking position whereby the permutation disks or tumblers will be relieved of any strain or stress in an attempt to force the withdrawal of the locking bolt.

A further object of the invention is to provide improved means for automatically locking the bolt in its locking position thereby necessitating a reoperation of the permutation members after each locking operation.

A further object of the invention is to provide improved means for securing the cover of the housing or casing containing the permutation mechanism in place.

With the above primary and other incidental objects in view as will more fully appear in the specification, the invention consists of the features of construction, the parts and combinations thereof and the mode of operation or their equivalents as hereinafter described and set forth in the claims.

Referring to the drawings, Figure 1 is a perspective view of the assembled lock inclosed in the housing or casing. Fig. 2 is a

front elevation of the lock with the cover of the housing removed. Fig. 3 is a side elevation of the mechanism, the housing being shown in section. Fig. 4 is an elevation of the inner side of the cover of the housing. Figs. 5 and 6 are detail views of the plungers by which the permutation disks are advanced throughout their step by step movement, one of the disks and its ratchet wheel being also shown in Fig. 5. Fig. 7 is a detail view of the adjustable stop arm of the permutation disks whereby the combination may be readily varied. Figs. 8, 9, 10 and 11 are detail views illustrating successive steps in the operation of the permutation mechanism. Fig. 12 is a detail perspective view of the cover locking mechanism.

Like parts are indicated by similar characters of reference throughout the several views.

In constructing the lock there is employed a casting or housing comprising a circular portion 1 from which projects a rectangular offset portion 2. Centrally located within the circular portion 1 is the main shaft 3 upon which are pivoted a plurality of independently revolvable permutation disks or tumblers 4. These revolvable permutation disks or tumblers control the reciprocatory movement of a locking bolt 5 mounted in and projecting beyond the rectangular offset portion 2 of the housing. Secured to each of the permutation disks or tumblers 4 is a ratchet 6 adapted to be engaged by a finger or pawl 7 carried by a reciprocating plunger 8 radially mounted in the casting or housing 1. There is provided a plunger 8 and pawl 7 for each of the permutation disks or tumblers. The plungers 8 are mounted to reciprocate in bearing sleeves 9 secured to and projecting inward from the annular wall of the casting 1. Within the bearing sleeves 9 are provided retracting springs 10 against the tension of which the plungers 8 may be depressed. The plunger 8 is provided with a central bore in which is located a helical spring 11 bearing upon the edge of the pawl 7 and tending to maintain the pawl 7 in its normal position. The inner ends of the sleeves 9 are slotted to receive the pawls 7 which slide within such slots when the plungers 8 are depressed.

Upon the depression of the plunger 8 against the tension of the retracting spring 10 the pawl or finger 7 engages the ratchet disk 6

and serves to rotate the ratchet disk 6 and with it the permutation disk or tumbler 4 a distance of one step. By repeatedly depressing the plunger 8 the permutation disk 5 may be advanced any predetermined number of spaces or steps.

Formed in the periphery of each of the permutation disks 4 is a series of shallow notches or recesses 12 arranged in such relation one with the other as to correspond with the teeth of the ratchet disks. Mounted upon the main shaft 3 adjacent to each of the permutation disks 4 is a stop arm 13 having an elongated opening 14 through which the shaft 3 extends. A spring arm 15 projects within the elongated opening 14 and bears against one side of the shaft 3. The arm 13 carries a lug 16 adapted to engage in any one of the series of recesses or notches 12. The stop arm 13 may be shifted in a radial direction against the tension of the spring arm 15 such movement being permitted by the elongated opening 14. By the radial movement of the stop arm 13 the lug 16 will be disengaged from the notch or recess 12 whereupon the stop arm may be revolvably adjusted to different radial positions and engaged in a different notch or recess 12.

Projecting from the rear wall of the housing or casing 1 is a stop post 17 adapted to be engaged by the stop arms 13 to limit the rotation of permutation disks 4 in one direction. The stop post 17 determines the initial or starting point for the operation of the disks in working the combination.

As shown in Fig. 2 the successive disks upon the main shaft 3 are cut away to expose the notched or recessed periphery of the disk below. The notches or recesses of the disks 40 are numbered from 1 to 9. By cutting the successive disks away whereby the lower disks will project beyond the uppermost disks the notches and indications will be visible enabling the operator to more readily adjust the stop arm 13 to the desired position upon the disk. In addition to the notches or recesses 12 each of the permutation disks or tumblers 4 are provided with a deep notch 18. The locking bolt 5 is adapted 50 to be released when the several permutation disks have been rotated to bring their notches 18 to a predetermined position and in alinement one with the other.

Mounted upon a stud 19 projecting from the rear wall of the housing 1 is a pawl arm or detent 20 adapted to engage a recess 21 in the reciprocating bolt 5 to maintain the bolt 5 in its outermost or locking position. The pawl arm or detent 20 is spring pressed 60 into engagement with the bolt by a spring 22.

Pivoted upon the same stud 19 with the pawl arm or detent 20 is a trip arm or lever 23 carrying a transverse stud 24 which engages and rides upon the periphery of the disks 4 65 as said disks are rotated. The trip arm or

lever 23 and stud 24 are spring pressed toward the disks 4 by a spring 25 of greater tension than the pawl arm spring 22. A finger 26 projects from the trip arm 23 and engages a stud or pin 27 carried by the pawl arm or detent 20. When the permutation disks 4 have been independently rotated by the repeated depression of the plungers 8 until the recesses 18 of the disks have been brought into alinement one with the other and 70 in registry with the stud 24 carried by the trip arm 23 the spring 25 will then cause the stud 24 to enter the registered recesses 18 oscillating the trip arm or lever 23 as indicated by dotted lines in Fig. 2. Inasmuch as the spring 25 is of greater strength than the spring 22 the finger 26 carried by the trip arm 23 and engaging the pin 27 will cause the pawl arm 20 to be withdrawn from the notch 21 of the bolt 5, against the tension of 85 the spring 22 when the stud 24 of the trip arm falls into the recesses 18. The bolt 5 will thus be released and then may be reciprocated within the casing 2 by means of the knob or handle 28 from the stem of which 90 projects an arm 29 engaging a stud 30, projecting laterally from the bolt 5.

Projecting longitudinally from the inner extremity of the bolt 5 is a pin 31. Revolvably mounted upon the main shaft 3 in a 95 common plane with the pin 31 and adjacent to one of the permutation disks 4 is a throw-out disk 32 adapted by its operation to disengage the stud 24 of the trip arm 23 from the notches 18 to release the permutation disks and permit their return to normal position and at the same time to release the pawl arm 20 to permit its return to engagement with the bolt 5 under the influence of the spring 22. Successive steps in the operation 100 of the throw-out disk are illustrated in Figs. 8, 9, 10 and 11. The throw-out disk 32 being mounted upon the main shaft 3 adjacent to the permutation disks 4 is provided with an arcuate slot 33 engaged by a stud 34 projecting from the adjacent permutation disk 4 or preferably from the ratchet disk 6. The arcuate slot 33 will permit the throw-out disk 32 a limited revoluble movement independent of the permutation disk. This independent movement of the throw-out disk is preferably made equal to one advance step of the permutation mechanism. In the periphery of the throw-out disk 32 there is provided a notch or recess 35 movable into and out of registry with the corresponding notch 18 of the permutation disk by the independent movement of the throw-out disk. 115

In Fig. 8 the parts are shown in their normal or starting position, in which the notches or recesses 35 and 18 are out of registry with each other. The initial advance step of the permutation disk will be made independent of the throw-out disk. During such initial step the stud 34 carried 120

by the permutation disk will move throughout the length of the arcuate slot 33 in the throw-out disk and the notch 18 of the permutation disk will move into registry with the notch 35 of the throw-out disk. The permutation disk and throw-out disk will thereafter move in unison throughout the subsequent forward operation of the mechanism. This simultaneous movement will be caused by the engagement of the stud 34 with the forward end of the arcuate slot 33.

In Fig. 9 the parts have been shown in their relation at the completion of the initial forward movement. Successive operations of the plunger 8 will advance the disks 4 and 32 until the aligned notches 35 and 18 are brought into registry with the stud 24 of the trip arm 23 whereupon the stud 24 will enter into said aligned notches thereby causing the withdrawal of the pawl arm 20 from engagement with the bolt 5 as before described and as shown in Fig. 10. In addition to the notch or recess 35 the throw-out disk 32 is provided with a recess 36, the cam shaped wall 37 of which is engaged by the pin 31 of the bolt 5 as said bolt is reciprocated toward the disk. The engagement of the pin 31 upon the cam shaped wall 37 of the notch 36 will rotate the throw-out disk a limited distance independent of the permutation disk. This limited advance movement of the throw-out disk is permitted through the engagement of the stud 34 in the arcuate slot 33. The shifting movement of the throw-out disk brings the stud 34 into engagement with the opposite end of the arcuate slot 33 and at the same time by bearing upon the stud 24 presses said stud 24 of the trip arm 23 out of the registered notches 18 and 35 and advances the notch 35 out of registry with the notches 18. The stud 24 then bears upon the periphery of the throw-out disk and permits the rotation of the permutation disks to move the notches 18 out of registry with the stud 24. After having been disengaged from the notches 18 the stud 24 will ride upon the periphery of the permutation disks 4 during their return movement to normal position. It is obvious, however, that this return movement of the disk cannot occur until the bolt 5 has been reciprocated to its locking position by the rotation of the knob or handle 28. The disengagement of the stud 24 from the notches 18 and 35 releases the pressure of the finger 26 of the trip lever from the pin 27 of the pawl arm 20 thereby permitting the pawl arm 20 to return to engagement with the bolt 5 under the influence of the spring 22. As the bolt 5 is reciprocated outward the pawl arm 20 will engage successively the notches 21 thereby preventing the return movement of the bolt 5 until the permutation disks have been again adjusted to permit the oscilla-

tion of the trip arm 23 and the withdrawal of the pawl arm 20. The notches 12 in the periphery of the permutation disks 4 and the notch 18 therein are so arranged in relation with each other and with the positions of the stud 24 and post 17 that the necessary number of advance steps required to bring the notch 18 into registry with the stud 24 will correspond with the particular notch 12 engaged by the stop arm 13. Thus if the lug 16 of the stop arm 13 is engaged with the fourth notch 12, four advanced steps or operations will be required to bring the notch 18 to position to be entered by the stud 24, while if the lug 16 is engaged with the sixth notch of the series, six such advance operations will be necessary. Thus by withdrawing the lug 16 of the stop arm 13 from engagement with a particular notch and rotating the stop arm 13 until the lug 16 may be engaged with a different notch the necessary number of advance steps to bring the disk to unlocking position will be varied thus providing means for readily changing the combination.

In order to return the permutation disks to the initial or starting position after each operation there is provided upon the inner side of the housing cover 38 a revoluble disk 39 carrying a laterally projecting arm 40 adapted to engage the stop arms 13 upon the rotation of the disk 39 and to return such stop arms into contact with the stop post 7. The disk 39 and arm 40 are oscillated by means of a handle or knob 41 upon the exterior of the housing cover. A stop pin 42 limits the oscillation of the disk 39 and arm 40 in one direction.

The housing cover 38 is provided with a lock to be operated by a key, but such key lock can only be operated after a prior operation of the permutation mechanism. The cover plate 38 is provided with a lug 43 adapted to engage an opening in the wall of the housing. Projecting inward from the rear wall of the housing is a plate 44 having formed therein a bearing for the reciprocating bolt 5 and also an opening 45 to be engaged by the key operated lock mechanism. Mounted in a sleeve 46 projecting inward from the lower portion of the cover plate 38 is a revoluble cylinder 47, having therein a key slot 48 whereby the cylinder may be rotated within the sleeve. The sleeve 46 is provided with a peripheral slot 49 through which projects a lug 50 carried by the revoluble cylinder 47. When the cylinder 47 is rotated in one direction the lug 50 is caused to engage in the opening 45 of the plate 44. By a reverse rotation of the cylinder 47 the lug 50 is carried out of the opening 45 and away from the plate. Pivoted upon the inner side of the cover plate 38 adjacent to the sleeve 46 is a detent 51 engaging in a notch or recess 52 in the

revoluble cylinder 47 and normally preventing the rotation of the cylinder within the sleeve. The construction is such that the cylinder may be rotated only after the detent 51 has been oscillated out of engagement with the recess 52. To oscillate the detent 51 there is provided within the locking bolt 5 a spring pressed deppresible pawl 53. The detent 51 is provided with a laterally projecting lip 54 extending into the path of the pawl 53 carried by the bolt. As the bolt 5 is reciprocated inward to its unlocked or inoperative position by the rotation of the knob 28 the pawl 53 will engage the lip 54 of the detent 51 and will oscillate the detent 51 out of its engagement with the revoluble cylinder 47 thereby permitting the cylinder to be rotated to withdraw the lug 50 from the plate 45. The detent 51 after being withdrawn from the revoluble cylinder will resist further oscillatory movement through the engagement of one arm of the detent with the under side of the sleeve 46. After having oscillated the detent 51 from engagement with the cylinder and thereafter meeting with resistance the deppresible pawl 53 will yield against the tension of its spring and will pass by the lip 54 of the detent as the bolt 5 continues to move inward. Upon a return movement of the bolt the pawl 53 will ride over the lip 54 without affecting the detent 51. Thus it will be seen that in order to remove the cover 38 from the housing it is necessary to first operate the combination of the permutation mechanism and then reciprocate the bolt 5 until the pawl 53 engages and oscillates the detent 51 out of engagement with the revoluble cylinder 47, while the detent is thus held out of engagement the cylinder may be rotated by means of a key to withdraw the lug 50 from its engagement with the plate 44.

From the above description it will be apparent that there is thus produced a device of the character described, possessing the particular features of advantage before enumerated as desirable, but which obviously is susceptible of modification in its form, proportion, detail construction, and arrangement of parts, without departing from the principle involved or sacrificing any of its advantages.

While in order to comply with the statute, the invention has been herein described in language more or less specific as to certain structural features, it is to be understood that the invention is not limited to any specific details, but that the means and mechanism herein shown and described comprise but one mode of putting the invention into effect and the invention is therefore claimed broadly in any of its possible forms or modifications within the scope of the appended claims.

Having thus described my invention, I claim:

1. In a permutation lock, a movable locking bolt, a plurality of independently adjustable permutation tumblers, a detent adapted to engage the bolt to maintain it in its locked position, and interengaging means between the detent and permutation disks, whereby the detent may be disengaged from the bolt only when the disks have been adjusted to predetermined relative positions, substantially as specified. 70

2. In a permutation lock, a movable locking bolt, a plurality of independently adjustable permutation tumblers, a detent spring pressed into engagement with the bolt and adapted to maintain the bolt in its locking position, a retracting spring of greater tension than that of the detent spring adapted to cause the withdrawal of the detent, said retracting spring being normally effective and means to render the retracting spring effective upon the adjustment of the permutation tumblers to predetermined positions thereby causing the detent to be disengaged from the bolt, substantially as specified. 80

3. In a permutation lock, a movable locking bolt, a plurality of independently adjustable permutation tumblers, a pivoted detent spring pressed into engagement with the locking bolt to maintain the bolt in its locking position, a pivoted lever which engages with said detent to withdraw the detent upon the oscillation of the lever, a spring of greater tension than the detent spring tending to oscillate the lever to withdraw the detent, the oscillation of the lever being limited by the permutation tumblers until the tumblers have been adjusted to predetermined positions whereupon the spring will oscillate the lever to cause the withdrawal of the detent against the tension of the detent spring, substantially as specified. 95

4. In a permutation lock, a movable locking bolt, a plurality of independently adjustable permutation tumblers controlling the movement of the bolt, adjustable stops carried by the permutation tumblers and adapted to be engaged therewith in different positions to vary the movement of the tumblers necessary to release the bolt, the superposed tumblers being recessed to expose to view the positions of engagement of the adjustable stops with the tumblers beneath, substantially as specified. 100

5. In a permutation lock, a movable locking bolt, a plurality of independently adjustable permutation tumblers controlling the movement of the bolt, adjustable stops carried by the permutation tumblers and adapted to be engaged therewith in different positions to vary the movement of the tumblers necessary to release the bolt, a portion of each succeeding tumbler being ex- 115 120 125 130

ended beyond the periphery of the preceding tumbler to expose to view the indicated positions of engagement of the adjustable stops with the tumblers substantially as specified.

6. In a permutation lock, a movable locking bolt, a plurality of concentrically pivoted independently revolvable permutation disks normally preventing the movement of the bolt but adapted to release the bolt when adjusted to predetermined relative positions, a ratchet wheel carried by each of the disks, a plurality of radially disposed reciprocating plungers one such plunger for each tumbler, a pawl carried by each plunger and adapted to engage the ratchet wheel of the corresponding tumbler to advance the tumbler at each operation of the plunger, a sleeve in which the plunger is mounted, 20 said sleeve being slotted at its extremity for the reception of the pawl, said pawl being adapted to engage the end of the slot upon each retrograde movement to insure the proper positioning of the pawl to engage the sleeve during its next operation substantially as specified.

7. In a permutation lock, a movable locking bolt, a plurality of concentrically pivoted independently revolvable permutation disks normally preventing the movement of the bolt but adapted to release the bolt when adjusted to predetermined relative positions, a ratchet wheel carried by each of the disks, a hollow reciprocating plunger for each of the tumblers, a pawl pivotally carried by each plunger, a retracting spring against the tension of which the plungers are depressed, and a retracting spring for the pawl located in the central bore of the 20 plunger substantially as specified.

8. In a permutation lock, a movable locking bolt, a plurality of independently adjustable permutation tumblers, a bolt controlling member adapted to release the bolt when the tumblers have been adjusted to predetermined relative positions, a throw out member adjustable independently of the tumblers and adapted by its movement to restore the bolt control member whereby the bolt will be engaged upon its return to locking position, said throw out member being operated by the movement of the bolt from locking to unlocking position, substantially as specified.

9. In a permutation lock, a movable locking bolt, a plurality of concentrically pivoted independently revolvable permutation disks each having a recess therein, a bolt control member adapted to enter the recesses of the permutation disks and thereby release the bolt when said disks have been adjusted to prevent their recesses in predetermined positions, a throw-out disk pivoted independently with the permutation disks to enter the recesses with which the

recesses of the permutation disks register when adjusted to releasing positions, said throw-out disk being capable of movement independent of the permutation disks whereby the recess of the throw-out disk will be moved out of registry with the permutation disks, thereby expelling the bolt control member from said recesses and restoring it to locking position, and means to independently shift the throw-out disk, 70 substantially as specified. 75

10. In a permutation lock, a movable locking bolt, a plurality of independently adjustable permutation tumblers, each having a recess therein, a throwout member adjustable independent of the tumblers and having a recess movable into and out of registry with the recesses of the permutation tumblers, a bolt control member adapted to enter the registered recesses to release the bolt, 80 said bolt control member being expelled from the recesses and restored to locking position by the independent movement of the throwout member, and means to shift the throwout member, substantially as specified. 85

11. In a permutation lock, a movable locking bolt, a plurality of independently adjustable permutation tumblers, a detent adapted to lock the bolt against movement, a trip lever adapted by its oscillation to disengage the detent from the bolt, said trip lever being normally locked against movement by the permutation tumblers until said tumblers have been adjusted to predetermined positions, a throwout member adjustable independently of the tumblers and adapted by its independent movement to restore the trip lever whereby the detent will be again influenced to engage the bolt, 95 and means to independently move the throwout member. 100

12. In a permutation lock, a movable bolt, a detent adapted to lock the bolt against movement, a spring tending to move the detent into engagement with the bolt, a retracting spring of greater tension than the engaging spring adapted to withdraw the detent from engagement with the bolt against the tension of the engaging spring, a plurality of independently adjustable permutation tumblers adapted when adjusted to predetermined positions to release the retracting spring thereby causing the bolt to be disengaged, and a throwout member adjustable independently of the tumblers 110 adapted by its movement to restore the retracting spring thereby permitting the detent to be returned to engaging position by the first mentioned spring, substantially as specified. 115

13. In a permutation lock, a movable bolt, a locking detent for the bolt movable into and out of engaging position, a plurality of independently adjustable permutation tumblers adapted when adjusted to predetermined positions to release the retracting spring thereby permitting the detent to be returned to engaging position by the first mentioned spring, substantially as specified. 120 125

mined positions to permit the withdrawal of the detent from engaging position, and a throwout member capable of adjustment independent of the tumblers adapted by its movement to permit the return of the detent to engaging position and means for shifting the throwout member, substantially as specified.

14. In a permutation lock, a movable locking bolt, a plurality of independently adjustable permutation tumblers adapted to release the bolt when adjusted to predetermined positions, a throwout member connected with one of the permutation tumblers whereby the initial movement of the tumbler will be independent of the throwout member but the subsequent movement of the tumbler will move the throwout member in unison therewith to the releasing position, and means to shift the throwout member an additional movement beyond the releasing position to effect the relocking of the bolt, substantially as specified.

15. In a permutation lock, a movable locking bolt, a plurality of independently adjustable permutation tumblers controlling the movement of the bolt, a housing in which said parts are contained, a cover for said housing, a key operated lock for said cover, a detent normally preventing the operation of the key operated lock and means for withdrawing said detent by the movement of the locking bolt to predetermined position, substantially as specified.

16. In a permutation lock, a movable locking bolt, a plurality of independently adjustable permutation tumblers controlling

the movement of the bolt, a housing in which said parts are contained, a cover for said housing, a key operated lock for said cover, including a movable locking member, a detent normally engaging the key operated locking member to prevent the operation thereof, a pawl carried by the locking bolt adapted to engage the detent to withdraw it from engagement with the key operated locking member when the bolt has been adjusted to predetermined position, substantially as specified.

17. In a permutation lock, a movable locking bolt, a plurality of independently adjustable permutation members controlling the movement of the bolt to and from locking position, means for moving the permutation members through step by step movements, comprising a reciprocatory plunger for each of the permutation members, a pawl pivotally carried by each of the plungers, said pawl being capable of oscillatory movement about its pivotal connection with the plunger, and a stop engaged by the pawl upon the retrograde movement of the plunger to oscillate the pawl through a return movement to its normal engaging position after having been oscillated therefrom, substantially as specified.

In testimony whereof, I have hereunto set my hand this 18th day of September 1912.

BERNARD H. ZIEHLER.
